UNITED STATES PATENT OFFICE.

LEWIS W. BROWN, OF EUGENE, OREGON.

DESIGN FOR AN EGG-SEPARATOR OR LEMON-SQUEEZER.

SPECIFICATION forming part of Design No. 34,342, dated April 9, 1901.

Application filed March 9, 1901. Serial No. 50,528. Term of patent 7 years.

To all whom it may concern:

Be it known that I, LEWIS W. BROWN, a citizen of the United States, residing at Eugene, in the county of Lane and State of Oregon, have invented a new and original Design for an Egg-Separator or Lemon-Squeezer, of which the following is a specification, reference being had therein to the accompanying drawings.

10 My invention relates to a new and original design for a lemon-squeezer or egg-separator, and I have illustrated the same in the accompanying drawings.

Referring to the drawings, Figure 1 is a 15 side elevation of the device. Fig. 2 is a top plan view thereof. Fig. 3 is a bottom plan view, and Fig. 4 is a central vertical transverse section.

In said drawings, 1 is a circular disk having a concentric groove 2 in the upper and in the lower face thereof, said grooves being arranged one above the other. A dome-like projection or knob 3 extends from one face of the disk, said knob being hollow and encir-

25 cled by a groove 4, as shown. The opposite face or side of the disk 1 is dished out at the center and about the inlet to the knob 3, as shown at 5. A series of ribs 6, which are angular in cross-section, extend from the apex of the dome to the base thereof, and shorter 30 ribs 7 are arranged therebetween. These last-mentioned ribs do not extend to the base of the dome, as slots 8 are formed therebelow; as shown, said slots opening into the interior of the dome. A series of curved slots 9 are 35 formed within the annular groove 4, said slots being concentric to the center of the disk.

Having thus described my invention, what I claim as new, and desire to secure by Letters Patent, is—

40 The design for an egg-separator or lemon-squeezer, as herein shown and described.

In testimony whereof I affix my signature in presence of two witnesses.

LEWIS W. BROWN.
